VACUUM FLASK SEALING MACHINE

Charles Eisler, South Orange, N. J.

Application October 1, 1949, Serial No. 119,155

2 Claims. (Cl. 49—1)

1

This invention relates to improvements in vacuum flask sealing machines. The invention is particularly designed to provide a novel machine for forming vacuum flasks and for molding the same from an inner flask and an outer blank.

The invention provides a novel molding unit and means for actuating same, and novel means for preforming the flask.

Pursuant to the invention, vacuum flasks may be produced with a high degree of accuracy on a machine which lends itself to production line use.

These and other advantageous objects, which will appear from the drawings, and from the description hereinafter, are accomplished by the structure of my invention, of which embodiments are illustrated in the drawings. It will be apparent, from a consideration of said drawings, and the following description, that the invention may be embodied in other forms suggested thereby, and such other forms as come within the scope of the appended claims are to be considered within the scope and purview of the instant invention.

In the drawings:

Fig. 1 is a schematic elevational view, partly sectional, showing successive stages of sealing vacuum flasks pursuant to the instant invention.

Fig. 2 is a top plan view of a machine embodying the invention, having stages or positions numbered with Roman numerals to correspond to those shown in Fig. 1.

Fig. 3 is a top plan view of a device for operating the molds and shaping rollers, pursuant to the invention.

Fig. 4 is a partly sectional, elevational view of the sealing head of the machine, the inner flask and the outer blanks being shown in position.

Fig. 5 is an elevational view of a sleeve for retaining the outer blank.

Fig. 5-A is a transverse sectional view thereof, taken on line A—A of Fig. 5.

Fig. 6 is an elevational view of the molding and lip forming mechanism.

Fig. 7 is a vertical sectional view of the neck and lip forming molds.

Fig. 8 is a plan view of the molds in closing position.

Fig. 9 is a schematic showing of means for operating the shaping rollers, the reference numbers V, VI, VII, IX indicating the parts at correspondingly numbered positions or stations in Figs. 1 and 2.

Fig. 10 is a perspective view showing the driving roller and its operating means, these parts

2

being also shown at position VII of Figs. 2 and 9, and

Fig. 11 is an elevational view showing the shaping roller preceding the driving roller and the means for operating it.

The object of the invention is to effect the sealing of a vacuum flask or bottle by the means described hereinafter.

Fig. 2 illustrates one form of the machine, 10 which includes the table 15 on top of which is disposed the spider 16, secured to the index plate 18 fixed to the sleeve shaft 19, actuated by an indexing device, such as the barrel cam 17. On the inner shaft 20 is mounted a large spur gear 20a for rotating the sealing heads. The shaft 20 has keyed thereto bevel gear 21 meshing with bevel gear 22 on shaft 23, the latter shaft being rotated by any suitable means, such as the belt and pulley transmissions 24 and 25. The pulley 25 is mounted on shaft 26, on which is also mounted the barrel-cam 17. Shaft 26 is rotated by any suitable means, such as by the worm 28 on the shaft 29 driven by belt transmission 30—31 from motor 32, engaging the wormgear 27 of shaft 26. The above described transmission or an equivalent may be used for the purpose mentioned.

The spider 16 carries a plurality—for example, twelve—sealing heads 33, some of which are shown in Fig. 2 in dotted lines. The twelve positions, designated by Roman numerals, are the loading position I and the unloading position XII, and intermediate positions II, III, IV, V, VI, VII, VIII, IX, X and XI.

35 Each of the sealing heads (Fig. 4) has an upper head 34 for retaining the flask and a lower head containing the guides for the lifting rod and the sealing rod. The vacuum bottle and the sealing rod are constantly rotating except at the molding position X, the unloading position XII, and the loading position I, at which stations their rotation is stopped by means hereinafter mentioned and illustrated in Fig. 4.

The outer blank 13 is retained in the resiliently expandable sleeve 35 having slots 36 (Fig. 5) which is clamped around the outer blank by means of the clamping ring 37 and the screw-and-lever, bolt means, or the like 38. The sleeve 35 has a flange 39 unitary therewith or united thereto, said flange being secured by means, such as bolts 40, to the top ring 41 resting on the top spur gear 42 and entrained thereto by means of the pins 42a, the top spur gear running on ball-bearings 34a in the top frame 34 (Fig. 4).

50 The inner flask 12 is supported interiorly on the

top collar 47 of the lift rod 46 which also carries the centering collar 48 fitting into the neck of the flask. At its lower extremity, lift rod 46 carries collar 56 riding on track 57 (Figs. 1 and 4).

The outer blank 13 and inner flask 12 are supported in the machine in inverted relation, as shown in Fig. 4, with the inner flask telescoped within the outer flask, the neck portion 12a of said inner flask constituting the lowermost part thereof. The sealing collar 49 is mounted on the inner sleeve shaft 50 in which the lift rod 46 is axially slideable and co-rotative, by means of the key 51 in said sleeve 50 engaging the keyways 51a in the rod.

The inner sleeve 50 is axially slideable in and co-rotative with the outer sleeve 52 by means of key 53 in the outer sleeve shaft engaging a keyway in the inner sleeve 50, the sleeve shaft 52 being rotatable in bushing 54 of lower head bracket 55. The inner sleeve 50 carries mushroom collar 58 riding on double track 59.

Rotation of the flasks, lift rod and sealing rod is effected as follows: Top spur gear 42, which carries the flask retainer 35, is driven by pinion 43 on shaft 44. Shaft 44 carries a similar pinion 60 which drives spur gear 61 keyed to the outer sleeve shaft 52. Shaft 44 also carries pinion 62 driven by the large spur gear 20a (Figs. 4 and 2). Pinion 62 is mounted on or integral with the slip clutch body 63 housing the rotatable slip clutch disc 64 mounted on shaft 44. Frictional entrainment of the slip disc 64 is effected by the fiber plugs 65 in the clutch body 63, which are held in contact with the disc 64 by the annular spring 66.

Stopping of the sealing head parts is effected by stop lever 67 carrying roller 68 and mounted on outer sleeve 52. When roller 68 contacts the stop rail 69 at molding position X, unloading position XII, and loading position I (Figs. 1 and 2), the outer sleeve 52, gear 61, pinion 60 and shaft 44 are thereby prevented from rotating, as is also the clutch disc 64. Pinion 62, driven by gear 20a, and clutch body 63, continue to rotate without interference by reason of the slippage between disc 64 and fiber plugs 65. Other, equivalent slippage means may be substituted therefor within the scope of this invention.

Fig. 1 schematically shows the sealing process in a straight line production arrangement. Loading is effected at position I, wherein the lift rod 46 is still partially retracted, the collar 56 resting on the sloped portion 57a of track 57. The sealing collar 49 is also down and the mushroom collar 58 on inner sleeve shaft 50 rests on the sloped portion 59a of the double track 59.

The inner flask 12 has the neck 12a and the flared mouth 12b, and is provided on top with the spacing pads 12c. It is placed by the operator on the top collar 47 of the lift rod 46, the centering collar 48 entering the neck. This latter collar serves the double purpose of centering the inner flask and of preserving the shape of the neck during the sealing operations. The parts are so proportioned that, preferably, there is a slight space left between the flared mouth of the inner flask and the sealing collar 49, as shown in Fig. 4. The outer blank 13, equipped with the exhaust tube 13a at its top, is then manually inserted into the retainer or sleeve 35 and passed over the inner flask.

At position II, the inner flask is in process of being raised and is gently preheated by burners 160.

At position III, the inner flask has been raised to its proper elevation, both inner and outer flasks being maintained in this position by the horizontal portions of tracks 57 and 59, preheating being effected by additional burners 160.

At position IV, the outer blank is further heated by burners 161.

At position V, the outer blank is pre-constricted by the shaping roller 163 (see Figs. 1 and 9), heat being supplied by burners 161 as before.

At position VI, the outer blank is still further constricted by shaping roller 164, while heated by burners 161 as before.

At position VII, final constriction is effected by roller 165 until the outer blank contacts the flare of the inner flask, the constricted portion being kept in a plastic condition as before by burners 161.

At position VIII, the actual sealing and cutting off of the collet 170 is effected by the crossfire burners 162, the collet dropping down onto the plate 166 (Fig. 1), the sealing collar 49 having been raised in contact with the mouth of the flask by the raised portion 59b of track 59. While the sealing operation is in progress, compressed air is introduced into the vacuum chamber by the air ducts 70, which are lowered and connected with the flask-exhaust tubes 13a by any suitable automatic means, so as to preserve the shape of the bottle neck by internal pressure. Thus, the inner flask is fused to the outer blank at the flared mouth end of the inner flask.

At position IX, the neck of the bottle is pre-formed by the forming roller 71 (Figs. 1, 2 and 9) while the glass is being kept plastic by burners 72, the sealing collar 49 having been dropped to its lowest position by the gap in track 59 (Fig. 1).

At position X, the final forming of the bottle is effected by the molds 73 and 73a and 126 (Figs. 6, 7 and 8), heat being supplied from beneath by the vertical burners 75 (Fig. 1).

The sealed and formed bottle then passes to position XI, where it is annealed by burners 76.

It should be noted (Fig. 1) that in positions I—XI inclusive, the centering collar 48 is maintained in position interiorly of the neck of the inner flask.

After annealing at position XI, the lift rod 46 with its top collar 47 and centering collar 48 is entirely retracted from the bottle by the drop 57b of track 57, at position XII (Fig. 1) and the finished bottle is then removed from the retainers 35 by the operator for subsequent silvering and exhausting operations.

During the forming and molding processes, compressed air has been introduced into the vacuum space, from the compressed air manifold 74a (Fig. 2) as at the sealing position VIII, for the purpose stated.

60 *Device for operating, shaping and forming rollers (Figs. 1, 2, 9, 10 and 11)*

The driving roller 165 at position VII (Figs. 1, 2, 9 and 10) is mounted in a clevis 77 fixed to the arched arm 78 of lever arm 79 integral with the boss 80 movably mounted on the vertical shaft 81. Shaft 81 is revolvable in the sleeve shaft 82, which is journalled in the upright guide 83. The sleeve boss 85, which has an integral lever arm 86, is secured by set screw 84 to the sleeve shaft 82. Above the boss 80, there is mounted on the shaft 81 and secured thereto by a set screw 87 a boss 87. Boss 87 has an arm 88 to the free end of which a pin 88' is fixed, said pin supporting coil spring 89 bearing against arm 79. The up-

right guide 83 has an arm 90 carrying the adjustable stop pin 91 bearing against the arm 79. Thus, the arms 79 and 86 are moved scissor-wise responsive to the movement of shafts 81 and 82, respectively, turned in opposite directions by a suitable device, such as that illustrated in Fig. 3 and later described. On swinging the lever arm 79 inwardly toward blank 13, the roller 165 is urged by the spring 89 against the blank and produces the required constriction, the depth of which, however, is limitable by the adjustable stop 91 of arm 90. The master driving mechanism, above described, shown in Fig. 10, operates all the other rollers, as shown in Figs. 2 and 9.

At position V (Fig. 9), the single lever arm 92 is keyed to the single upright shaft 93 to which there is swivelly connected as at 95' block 95 in which rod 94 is slidably disposed, said rod being connected to the lower lever arm 86 of position VII. The rod 94 is movable in block 95 against tension of spring 96, which is adjustable as to compression by screw nuts 97 or the like on rod 94. When lever arm 86 of position VII moves in the direction of arrow D (Fig. 9), the lever arm 92 of position V is thus entrained in the same direction, by the spring 96 acting on block 95. Thus, roller 163 is urged against the glass blank 13, the depth of the resulting constriction in blank 13 being limited by the adjustable stop screw 98 on the guide 83a.

At position VI, the roller 164 is operated in a like manner by the connecting rod 99 swivelled as at 99' on the lever arm 86 and slidable in swivel block 100 on lever arm 101 against the tension of spring 102 adjustable as to compression by nuts 103 on rod 99. Lever arm 101 is keyed to vertical shaft 104 and limited as to motion in the direction of arrow D by adjustable stop pin 105 on guide 83b. The lever arm 106 is likewise keyed to shaft 104 and moves in unison with lever arm 101, whereby the roller 164 is urged into contact with the glass blank to effectuate the required constriction.

The device employed in position IX (at which the neck of the bottle is formed by forming roller 71) is similar to that used at position V, but since the connecting rod 107 is swivelled on the lower lever arm 86 at 99' at position VII, the reversing disc 108 is utilized. The connecting rod 107 is swivelled on lug 109 fixed to disc 108, and a second connecting rod 110 is swivelled as at 110' on the disc opposite to lug 109. The rod 110 is slidably in the swivel block 111 mounted on lever arm 112 against the tension of spring 115, adjustable by nuts 116. The swivel block is mounted on lever arm 112 opposite lever arm 113 which carries the forming roller 71, the stop pin 116 being provided on the guide 83c to limit the travel of the roller 71.

The burners (and flames) pass underneath the arched arms 78 of the roller carriers (Figs. 10 and 11), gas being supplied to the burners by the gas ducts 117 from the gas supply pipe 118 secured to the sides of the table (Fig. 2).

Molding device

The molding device shown in Figs. 6, 7 and 8 (and position X, Fig. 2) differs from the devices heretofore employed in bulb blowing machines, especially in the feature of the movable bottom mold. It comprises mold halves 73 and 73a, carried by mold arms 119 and 120, respectively. Arm 120 is keyed on the inner vertical shaft 121, and arm 119 is keyed on the sleeve shaft 122, the two shafts being rotated in opposite directions,

whereby the mold halves are alternately opened as shown in dotted lines at position X in Fig. 2, and closed as shown there and in Fig. 8 in full lines. Shaft 122 is journaled in the upright support 123, thrust bearings 124 and 125 being provided to eliminate friction between the mold arm hubs and the support. The mold additionally comprises the vertical cylindrical lip mold 126 (Fig. 7) slidable in the cylindrical recess 127 of the mold halves 73, 73a. The mold halves are provided with registering means so that when they are closed, as in Fig. 8, the registering means (pins 128) will assure their proper alignment for forming the neck of the vacuum bottle by the inner mold contour 129.

Any suitable device may be employed for rotating shafts 121 and 122 and thus swinging the mold halves 73, 73a and shafts 81, 82 of the master drive mechanism of Fig. 10 in opposite directions; such device is schematically shown in Figs. 3 and 6 for the mold halves and indicated at 171, Fig. 2, for the master drive mechanism of Fig. 10. To the shafts 121 and 122 are clamped the collars 145 and 146 respectively, swivelly connected at 145', 146' to levers 147, 147' swivelly connected as at 148' to block 148 which is reciprocated by rod 149, actuated by crank lever 150 having arm 151 to which the cam roller 152 is secured for following contact with cam 153 on shaft 154. Shaft 154 is shown rotated by bevel gear drive 155—155a on shaft 156, and belt drive 157 from shaft 26 (Fig. 3 and station X, Fig. 2).

The vertical lip mold 126, which has the circular lip forming groove 130, then moves up into contact with the bottle, whereby the lip is formed and smoothed. The vertical lip mold 126 consists of the halves 126a, 126b, which are movable in the cylindrical recess 127 defined by the lower ends of the mold halves 73, 73a. Levers 131 are carried by and pivotally connected to the mold halves 73, 73a as by pivot pins 131a, and have at one end rollers 131b engaging the grooves 131c of the vertical mold halves 126a, 126b. At their other ends, levers 131 are provided with rollers 131d. When the mold halves 73, 73a are closed (the levers 131 being carried by the mold halves), the rollers 131d of the levers will register with the open jaw ends 132a of the cross bar 132. When the mold halves are opened, the levers 131 are carried with the mold halves to the open position out of the path of the lift rods 46. The lip mold 126 is moved up (after the mold halves 73, 73a are closed) and retracted (after the mold halves have been opened) by suitable means such as by the levers 131 on shaft 132 engaging bracket 133 fixed on vertical shaft 134 (Fig. 6) guided in lugs 135 and raised and lowered by lever 136, vertical shaft 137 and cam lever 138, which is fulcrumed at 138' in bracket 139 fixed to table 15. Lever 138 carries cam roller 140, held in following contact with cam 141 by spring 142. The lip mold 126 has the holes 143 communicating with the funnel recess 144 for passing bits of glass in case the lip formed on the bottle should break in the process of molding.

During the molding operation, the molds are heated by the vertical burners 75 (position X, Fig. 1), the bottle remaining in the sealing head 33 as before. The sealing collar 49 is retracted (due to the break in track 59 past position VIII) before the molding operation at position IX.

The air ducts 70 which fit over the exhaust tubes 13a (Fig. 1) are carried by the air manifold 70a (Fig. 2) which is periodically raised and lowered by any desired or convenient lifting cam

device, and air is introduced by the economizer 158 in the usual way through the supply duct 159 connected with a main compressed air supply source.

Having thus described my invention, what I claim as new and desire to secure by Letters Patent is:

1. In a vacuum flask sealing machine, means for supporting an outer blank and an inner flask comprising the vacuum flask, in inverted relation with the inner flask telescoped within the outer blank, said inner flask having a neck portion which constitutes the lowermost portion thereof when said flask is supported in said inverted position, a molding unit comprising mold members movable into and out of closing position about the vacuum flask, and a vertical cylindrical lip mold adapted to be moved into engagement with the neck portion of the flask to form the same into a lip portion, said lip forming mold being provided with a circular groove at the upper end thereof, and being provided with a recess in the lower portion and with apertures opening into said recess.

2. In a vacuum flask sealing machine, means for supporting an outer blank and an inner flask comprising the vacuum flask, in inverted relation with the inner flask telescoped within the outer blank, said inner flask having a neck portion which constitutes the lowermost portion thereof when said flask is supported in said in-

verted position, and a molding unit comprising mold members movable into and out of closing position about the vacuum flask, said mold members having a cylindrical recess in the lower end thereof, and a vertical cylindrical lip mold adapted to be moved into engagement with the neck portion of the flask to form the same into a lip portion, said lip forming mold being provided with a circular groove at the upper end thereof, and being provided with a recess in the lower portion and with apertures opening into said recess.

CHARLES EISLER.
